INVENTOR:
Herman Henrichs

BY
Hugh K. Wagner,
ATTORNEY

UNITED STATES PATENT OFFICE.

HERMAN HENRICHES, OF ST. LOUIS, MISSOURI.

COMBINED PROTRACTOR AND SCALE.

1,409,342.

Specification of Letters Patent. Patented Mar. 14, 1922.

Application filed July 22, 1919. Serial No. 312,519.

To all whom it may concern:

Be it known that I, HERMAN HENRICHES, a citizen of the United States, residing at the city of St. Louis, in the State of Missouri, have invented certain new and useful Improvements in Combined Protractors and Scales, of which the following is a specification.

This invention may be called a combined 10 protractor and scale, and has for its object the provision of a mathematical instrument adapted to assist in the correct alinement of holes for bolts, rivets, and the like in structural steel or iron work or the like.

In the accompanying drawings forming 15 part of this specification, in which like numbers of reference denote like parts wherever they occur,

Figure 1 is a top plan view of this instrument;

Figure 2 is a side elevation showing the beams, uprights, struts, and plates used in metal frame-works for buildings;

Figure 3 is a front elevation of this instrument, looking at it in the way indicated by the arrows in the line 3—3 in Figure 1; and

Figure 4 is a sectional view taken on the line 4—4 in Figure 1, looking in the direction of the arrows.

Heretofore, it has been a difficult, tedious, and time-taking job correctly to lay out in alinement the bolt or rivet holes for the various parts in the metal framework of buildings and the like, and this work has necessitated the laying out of such work in full size,

30 on a shop floor or similar place. This has required large space and tiresome crawling and stooping. With the present instrument, given the height of the upright or the dis-

35 tance of one beam or cross-piece from another, the scale-bar 1 can be so moved upon the perpendicular bar 2 as to give the same effect of distance as in the actual construction, and by moving the protractor-arms 3

40 and 4 to an appropriate place upon the scale-bar 1, the same relative angle for the dimensions given will be assumed by the protractor or scale arms 3 and 4, relative to the scale-bar 1 and relative to the degrees 45 50 scale 5, as will be occupied by the struts 6 and 7 in the actual construction shown in Figure 2.

By means of the degree scale 5, the exact degree of angle of the arms 3 and 4 to the 55 base-scale arms 8 and bar 1 (or to the perpendicular arm 2) will be determined; and

that angle once ascertained is the same for the holes for bolts 9 and bolts 10 and is likewise the same for holes for bolts 11, 12, 13, 14, and 15. The angle having been thus determined, it is necessary only to mark the metal parts, without actually assembling the same, and, when elevated to the position where they are to be assembled in a building framework or the like, it will be found 60 that, the angle of the holes having been thus mathematically ascertained, the holes are in alinement and ready for use.

The perpendicular bar 2 is preferably fixed to the center plate 16 carrying the degree scale 5. The base-scale arms 8 are preferably pivoted to the screw 17. The arms 3 and 4 are pivoted on the said screw 17, and nuts 18 hold the said arms 3 and 4 and 8 upon the said center plate 16. In addition, 75 thumb-nuts 19 are provided to hold the arms 8 rigid and lengthwise, to hold the arms 3 and 4 rigid when desired, the lower end of each of the said thumb-nuts 19 being equipped with a notched nut 20, the lip 21 80 of which underlies and rides upon the underneath edge of the periphery of the degree scale 5. Ordinarily, the base-scale arms 8 will be fixed rigidly when a job is begun, and will remain as a base line, while the arms 3 85 and 4 are free upon their pivot 17.

Arm 1 is freely slidable upon the perpendicular bar 2, but can be fastened at any particular point upon the scale on bar 2 by means of the thumb-nut 22.

The bar 2 is composed of a relatively flat scale-part 23 and a track 24 adapted to slide in the groove 25 in the grip-member 26, to which bar 1 is attached by screws 27, which grip-member is also pierced by thumb-screw 90 95 22 for holding the bar 1 stationary upon bar 2 when desired.

It will be observed that the entire instrument can be knocked down so as to be comprised within very small space or a small 100 case or package by removing bar 1 from bar 2 and swinging arms 8 and arms 3 and 4 parallel with bar 2 and laying the separated arm 1 along in the same direction.

Having thus described this invention, I 105 hereby reserve the benefit of all changes in form, arrangement, order, or use of parts, as it is evident that many minor changes may be made therein without departing from the spirit of this invention or the 110 scope of the following claims.

The terms "perpendicular", "transverse",

"pivoted", and "base-scale" as used herein are predicated on the assumption that the two base-scale arms 8 are in the position shown in Figure 1 and that the bar 2 extends at a right-angle thereto, as shown in Figure 1. Thus the scale-bar 1 extends transversely to the bar 2 and the bar 2 is perpendicular thereto as well as to the base-scale arms 8. The arms 8 and the arms 3 and 4 are pivoted on screw 17 relative to the position of the said members shown in Figure 1. The relation of the bar 2 is fixed relative to the center-plate 16, which carries the degree scale 5. Thus a relatively stationary frame is provided by combination of the bar 2 and the center-plate 16. As the scale-bar 1 is fixed to bar 2 against pivotal or lateral movement and is made longitudinally slidable thereon, the bar 2 occupies permanently the relation of perpendicularity to the scale-bar 1. This enables the position of the arms 8 to be determined accurately as being either parallel to bar 1 and simultaneously perpendicular to bar 2 or as being at a different angle. Figure 1 shows the instrument as laid out before the user ready for use, and in that sense the arms 8 will be regarded substantially as its base. The pivot 17 and the mode of attachment thereto of arms 8 and arms 3 and 4 allow movement of any one of the said four arms in a pivoted manner on screw 17 to any angle relative to the fixed members 1 and 2 and the degree-scale 16.

35 I claim:

1. In an instrument of the character described, the combination of a member having a scale thereon, a second scale member adapted to be moved relative to the said first mentioned scale-member, a pivoted scale-arm adapted to co-operate with the said second scale member to determine dimensions, a degree scale fixed relative to the said first-mentioned scale member and a pair of arms pivoted with relation to the said first-mentioned scale member.
2. In an instrument of the character described, the combination of a member having a scale thereon, a second scale-member adapted to be moved relative to the said first-mentioned scale-member, a pivoted scale-arm adapted to co-operate with the said second scale-member to determine dimensions, a degree scale fixed relative to the said first-mentioned scale member a pair of arms pivoted with relation to the said first-mentioned scale member, and a base-scale arm attached to one or more of the aforesaid members.

60 3. In an instrument of the character de-

scribed, the combination of a member having a scale thereon, a second scale-member adapted to be moved relative to the said first-mentioned scale-member, a pivoted scale-arm adapted to co-operate with the 65 said second scale-member to determine dimensions, a degree scale fixed relative to the said first-mentioned scale-member, a pair of arms, and a base scale arm also pivoted with relation to said first-mentioned scale member, said degree scale being adapted to determine the angle of said pair of arms.

4. In an instrument of the character described, the combination of a member having a scale thereon, a second scale-member 75 adapted to be moved relative to the said first-mentioned scale-member, a pivoted scale-arm adapted to co-operate with the said second scale-member to determine dimensions, a degree scale fixed relative to 80 the said first-mentioned scale member, a pair of arms, and a pair of base scale arms also pivoted with relation to said first-mentioned scale member, said degree scale being adapted to determine the angle of said pair of 85 arms.

5. In an instrument of the character described, the combination of a member having a scale thereon, a second scale-member adapted to be moved relative to the 90 said first-mentioned scale-member, a pivoted scale-arm adapted to co-operate with the said second scale-member to determine dimensions, a degree scale fixed relative to the said first-mentioned scale member, a pair 95 of arms, a pair of base scale arms also pivoted with relation to said first-mentioned scale-member, and thumb-screws adapted to hold said scale arms stationary.

6. In an instrument of the character de- 100 scribed comprising in combination, a plate, a scale member having a track extending longitudinally thereon, a second scale member extending transversely across the first-named member and having a groove in its 105 intermediate portion slidably cooperable with said track whereby to permit adjustment of such transverse scale member along the first-named scale member, means for temporarily securing the transverse member 110 relative to the other scale member, a scale arm pivoted to the plate and movable freely with relation to the transverse scale member, and a degree scale carried by the plate and cooperable with the pivoted scale 115 member.

In testimony whereof I hereunto affix my signature.

HERMAN HENRICHES.
